CLAIM

The ornamental design for a device for operating a laser ablation catheter, as shown and described.

DESCRIPTION

Device for operating a laser ablation catheter

1.1 is a perspective view;

1.2 is a front view;

1.3 is a back view;

1.4 is a side view;

1.5 is a side view;

1.6 is a top view; and

1.7 is a bottom view.

In the drawings, the broken lines are for the purpose of illustrating environment only and form no part of the claimed design.
